UNITED STATES PATENT OFFICE.

ALBERT COWELL, OF KIDDERMINSTER, ENGLAND.

DESIGN FOR A CARPET-PATTERN.

Specification forming part of Design No. 5,711, dated March 26, 1872.

To all whom it may concern:

Be it known that I, ALBERT COWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This invention relates to a new ornamental back-ground for carpets; and consists in forming the same of two kinds of figures, A and B. Each figure A contains a central rosette, a, from which four leaves, b b, project diagonally, embraced within projecting scrolls c c. Each figure B contains a central rosette, d, projecting foliage e, and outer leaves ff, as shown.

I claim as my invention—

The design for the ground-work of a carpet, as shown.

ALBERT COWELL.
